AUTOMATIC TELEGRAPH KEY

Forrest A. Bartlett, Gardena, Calif.

Application May 30, 1944, Serial No. 538,074

6 Claims. (Cl. 178—82)

1

This invention relates to electric telegraph apparatus and especially to a transmitter key which is arranged automatically to send a series of dots or a series of dashes while the key is held by the operator on one side or the other, respectively, of the silent position.

My invention particularly relates to an improved fully automatic telegraph transmitter key unit which may readily be incorporated in any radio telegraph transmission circuit and which includes adjustments affording an unusual degree of adaptability to a variety of conditions of use.

An object of my invention is to provide a small self-contained transmitter key unit of the character described and of the type employing a side-swinging key lever, and which may be operated by any suitable source of electrical energy of substantially constant voltage.

A further object of my invention is to provide a self-contained transmitter key unit, fully automatic in operation, which may readily be incorporated in any transmitter set.

A further object of my invention is to provide a fully automatic telegraph transmitter key unit having means to vary the speed of sending within wide limits.

A further object of the invention is to provide a fully automatic telegraph transmitter key unit having means to adjust the characteristics of the impulses transmitted, i. e., having means to adjust the speed of the impulses transmitted, as well as the spacing between impulses and the relation existing between the length of the dots and the length of the dashes.

Further features of the invention will hereinafter appear in the specification following and will be pointed out specifically in the appended claims. The invention is herein described and illustrated with reference to specific embodiment illustrated and described by way of example only, but the scope of the invention is not in any way limited to the described embodiment except insofar as defined by the claims.

Referring to the drawings the single figure is a schematic diagram of a simplified electrical circuit for a fully automatic telegraph transmitter key unit embodying the principles of the present invention.

In the circuit illustrated the basic elements of my full automatic key unit are illustrated diagrammatically and comprise a transmitter key unit SW₁, a relay Ry, and a pair of condensers C₁ and C₂. The condenser C₂ has a capacity materially greater than that of the condenser

2

C₁; and both condensers C₁ and C₂ are connected in series with each other, and both condensers are also connected in series as by a circuit I with the coil 2 of the relay Ry. This circuit I is connected across both poles 3 and 4 of a suitable source of electrical energy E.

The key unit SW₁ is preferably of the single pole, double throw type, its blade 5 being mounted for movement to either side of its silent position so that it can make engagement optionally with either of two contacts a or b. Another double throw switch SW₂ has its blade 6 operably connected to the armature a of the relay Ry in such a manner that when the coil 2 is energized, the blade 6 makes engagement with the contact e, whereas, when the coil 2 is de-energized the spring 7 of an adjustable tensioning device T draws the blade 6 away from the contact e and into engagement with a contact f. The switch contact f is carried by an adjustment screw 8 whereby the length of stroke of the blade 6 can easily be varied.

Since the pole 4 of the source of energy E is grounded as indicated at 9, the fact that the armature A is connected as by a conductor 11 to the pole 4 results in permanently grounding of blade 6 of the switch SW₂.

The contact e of the switch SW₂ is connected as by a conductor 12 to one of the terminals 13 by means of which my improved transmitter key unit can be connected at the external circuit 14 to be keyed; the other terminal 16 being grounded as indicated at 17.

The adjustable contact f of the switch SW₂ is connected as by a conductor 21 which includes suitable resistance R₁ to the blade 5 of the switch SW₁. The switch contact a is connected as by conductor 22 with the conductor I between the coil 2 and the pair of condensers C₁ and C₂, whereas another conductor 23 connects the switch contact b to the circuit I between the two condensers C₁ and C₂. However, a variable resistance R₂ is shunted around the condenser C₁ so that switch contact b is always connected to the circuit I between condenser C₁ and the coil 2.

When key unit SW₁ is actuated by making engagement between the blade 5 and the contact a, the following circuit will be completed, to wit: the pole 3, coil 2, conductor 22, switch contact a, blade 5, conductor 21 including resistance R₁, adjustable switch contact f and blade 6 of the switch SW₂, conductor 11, and pole 4. Consequently, this circuit operates to shunt the two condensers C₁ and C₂ out of the circuit I. The

series combination C_1C_2 is effectively discharged by virtue of the short circuit established around the condensers by closing of the switch contact a . However, since the circuit which is completed by closing the contact a results in energizing the coil 2 of the relay R_y , the armature A will immediately be attracted, drawing the blade 6 away from the contact f and into engagement with the contact e , thus closing the external circuit 14. By moving the blade 6 away from the contact f , the circuit including the contact a is broken, thus breaking the short circuit around the series condenser combination C_1C_2 , thus re-establishing the circuit 1 which includes the capacity combination C_1C_2 with the result that the condensers will charge at a rate determined by their respective capacity. Accordingly, current will continue to flow through the coil 2 at a rate which greatly decreases as the charge of the capacity combination C_1C_2 builds up. Obviously, therefore, the magnetic force exerted by the coil 2 will, after the elapse of a period determined by the total value of the condenser combination C_1C_2 , reach a point where it is overcome by the tension in the spring 7, whereupon the blade 6 will again be retracted from the contact e and into engagement with the contact f , thus breaking the external circuit and re-establishing the circuit which includes the contact a , it being assumed, of course, that the blade 5 has been held closed. This cycle of events, therefore, will be repeated continuously as long as the blade 5 is held in engagement with the contact a . The periodicity at which the external circuit 14 will be closed will be varied by the tensioning device T whereby the tension in the spring 7 may be adjusted. The greater the tension, of course, the lesser will be the delay required before the force of the spring is able to overcome the magnetic attraction of the coil 2 and correspondingly the duration of closing the external circuit 14 will be decreased. On the other hand, by variation of the position of the adjustable contact f , the distance through which the blade 6 travels in moving from the contact e to the contact f can be varied, with the result that the interval between periods of closing of the external circuit 14 can similarly be varied.

When the blade 5 of the switch SW_1 is moved into engagement with the switch contact b , the circuit which includes the variable resistance R_2 will be completed again, thus causing energization of the coil 2. When the switch blade 5 is moved into engagement with the switch contact b , the following circuit will be completed, to wit: pole 3, coil 2, resistance R_2 , conductor 23, switch contact b , blade 5, conductor 21 including resistor R, contact 5 and blade 6, conductor 11 and pole 4. Therefore, the shunting effect produced by closing the contact b is the same as the previously described resulting in energizing coil 2, but with the exception that condenser C_2 is completely shunted out whereas the condenser C_1 is shunted out only to the extent determined by the value of the resistance R_2 . Since the effective capacity of a condenser acting singly is greater than that of a series condenser combination, the effect of shunting the condenser C_1 out of the circuit by the resistance R_2 is to increase the total condenser capacity of the circuit and similarly to increase the length of time required for that total condenser capacity to build up. Therefore, a greater length of time will be required for the spring 7 to overcome the magnetic attraction of

the coil 2 to withdraw the blade 6 from the contact e , with the result that the external circuit 14 will be closed for a period of greater duration than that resulting from engagement of the blade 5 with the contact a . However, these impulses of greater duration will be repeated in the external circuit 14 as long as the blade 5 remains in engagement with the contact b just as in the previously described operation involving the use of the contact a .

Thus it may be seen that so long as the switch blade 5 is kept in engagement with the contact a , a series of impulses of relatively short duration, i. e., dots, will be transmitted to the external circuit 14; whereas, so long as the blade 5 is kept in engagement with the contact e , a series of impulses of greater duration, i. e., dashes, will be transmitted to the external circuit 14.

The ratio of dot length to dash length is subject to variation by manipulation of the variable resistance R_2 .

I claim:

1. In an automatic telegraph transmitter key, a plurality of condensers, a conductor interconnecting said condensers, a relay comprising a solenoid, an armature cooperatively associated therewith, a pair of spaced contacts, a switch blade actuated by said armature to engage one of said contacts when said solenoid is energized, and spring means for moving said blade into the other of said contacts when said solenoid is de-energized, a conductor connecting said blade to one potential of a current source, a conductor connecting one terminal of said solenoid to the other potential of said current source, a conductor connecting the other terminal of said solenoid to one of said condensers, a key comprising a blade and a pair of key contacts optionally engaged by said key's blade, a conductor connecting one of said key's contacts to said conductor interconnecting said condensers, a conductor connecting the other of said key's contacts with said conductor connecting said solenoid to said condensers, a conductor connecting said key's blade to one of said relay's contacts, and means connecting the other of said relay contacts into an external circuit.

2. In an automatic telegraph transmitter key, a plurality of condensers, a conductor interconnecting said condensers, a relay comprising a solenoid, an armature cooperatively associated therewith, a pair of spaced contacts, a switch blade actuated by said armature to engage one of said contacts when said solenoid is energized, spring means for moving said blade into the other of said contacts when said solenoid is de-energized, and means for varying the force of said spring, a conductor connecting said blade to one potential of a current source, a conductor connecting one terminal of said solenoid to the other potential of said current source, a conductor connecting the other terminal of said solenoid to one of said condensers, a key comprising a blade and a pair of key contacts optionally engaged by said key's blade, a conductor connecting one of said key's contacts to said conductor interconnecting said condensers, a conductor connecting the other of said key's contacts with said conductor connecting said solenoid to said condensers, a conductor connecting said key's blade to one of said relay's contacts, and means connecting the other of said relay contacts into an external circuit.

3. In an automatic telegraph transmitter key, a plurality of condensers, a conductor interconnecting said condensers, a relay comprising a solenoid, an armature cooperatively associated therewith, a

pair of spaced contacts, a switch blade actuated by said armature to engage one of said contacts when said solenoid is energized, spring means for moving said blade into the other of said contacts when said solenoid is de-energized, and means for moving said other of said contacts to vary the distance traversed by said blade in making a contact therewith, a conductor connecting said blade to one potential of a current source, a conductor connecting one terminal of said solenoid to the other potential of said current source, a conductor connecting the other terminal of said solenoid to one of said condensers, a key comprising a blade and a pair of key contacts optionally engaged by said key's blade, a conductor connecting one of said key's contacts to said conductor interconnecting said condensers, a conductor connecting the other of said key's contacts with said conductor connecting said solenoid to said condensers, a conductor connecting said key's blade to one of said relay's contacts, and means connecting the other of said relay contacts into an external circuit.

4. In an automatic telegraph transmitter key, a plurality of condensers, a conductor interconnecting said condensers, a relay comprising a solenoid, an armature cooperatively associated therewith, a pair of spaced contacts, a switch blade actuated by said armature to engage one of said contacts when said solenoid is energized, and spring means for moving said blade into the other of said contacts when said solenoid is de-energized, a conductor connecting said blade to one potential of a current source, a conductor connecting one terminal of said solenoid to the other potential of said current source, a conductor connecting the other terminal of said solenoid to one of said condensers, a key comprising a blade and a pair of key contacts optionally engaged by said key's blade, a conductor connecting one of said key's contacts to said conductor interconnecting said condensers, a conductor connecting the other of said key's contacts with said conductor connecting said solenoid to said condensers, a conductor connecting said key's blade to one of said relay's contacts, a resistor, means connecting one terminal thereof to said other terminal of said solenoid, means connecting the other terminal of said resistor to said conductor interconnecting said condensers, and means connecting the other of said relay contacts into an external circuit.

5. In an automatic telegraph transmitter key, a plurality of condensers, a conductor interconnecting said condensers, a relay comprising a solenoid, an armature cooperatively associated therewith, a pair of spaced contacts, a switch blade actuated by said armature to engage one of said contacts when said solenoid is energized, and spring means for moving said blade into the other of said contacts when said solenoid is de-energized, a conductor connecting said blade to

one potential of a current source, a conductor connecting one terminal of said solenoid to the other potential of said current source, a conductor connecting the other terminal of said solenoid to one of said condensers, a key comprising a blade and a pair of key contacts optionally engaged by said key's blade, a conductor connecting one of said key's contacts to said conductor interconnecting said condensers, a conductor connecting the other of said key's contacts with said conductor connecting said solenoid to said condensers, a conductor connecting said key's blade to one of said relay's contacts, a variable resistor, means connecting one terminal thereof to said other terminal of said solenoid, means connecting the other terminal of said resistor to said conductor interconnecting said condensers, and means connecting the other of said relay contacts into an external circuit.

6. In an automatic telegraph transmitter key, a plurality of condensers, a conductor interconnecting said condensers, a relay comprising a solenoid, an armature cooperatively associated therewith, a pair of spaced contacts, a switch blade actuated by said armature to engage one of said contacts when said solenoid is energized, spring means for moving said blade into the other of said contacts when said solenoid is de-energized, and means for varying the force of said spring, a conductor connecting said blade to one potential of a current source, a conductor connecting one terminal of said solenoid to the other potential of said current source, a conductor connecting the other terminal of said solenoid to one of said condensers, a key comprising a blade and a pair of key contacts optionally engaged by said key's blade, a conductor connecting one of said key's contacts to said conductor interconnecting said condensers, a conductor connecting the other of said key's contacts with said conductor connecting said solenoid to said condensers, a conductor connecting said key's blade to one of said relay's contacts, a variable resistor, means connecting one terminal thereof to said other terminal of said solenoid, means connecting the other terminal of said resistor to said conductor interconnecting said condensers, and means connecting the other of said relay contacts into an external circuit.
